CLAIM

The ornamental design for a candle extinguisher with bendable nozzle, as shown and described.

DESCRIPTION

FIG. 1 is a top-front perspective view of a candle extinguisher with bendable nozzle in an environment of use, showing my new design;

FIG. 2 is a front elevation view thereof;

FIG. 3 is a rear elevation view thereof;

FIG. 4 is a left side elevation view thereof;

FIG. 5 is a right-side elevation view thereof;

FIG. 6 is a top plan view thereof;

FIG. 7 is a bottom view thereof;

FIG. 8 is a top-front perspective view thereof; and,

FIG. 9 is a bottom perspective view thereof.

The broken lines in FIG. 1, FIG. 6 and FIG. 8 depict environmental subject matter and form no part of the claimed design.

The "AIRYFAIRY" lettering and icon shown in broken lines is a registered trademark of Zlatko Vlasic.
